PAPER BOARD CHEST

Wilbur G. Anderson, Jr., Grand Rapids, Mich., assignor to American Box Board Company, Grand Rapids, Mich., a corporation of Michigan

Application April 21, 1947, Serial No. 742,842

5 Claims. (Cl. 229—44)

1

This invention relates to a novel structure of chest made from paper material, with an under chest receptacle having bottom and vertical sides and ends and open at the top, to which at the upper edge of one of the sides a cover is hingedly connected. The chest while it is conveniently used for carrying apples therein, separated from each other within the block by suitable cells also provided by paper board partitions, is not limited in use to receiving and carrying any specific article or articles.

It is an object and purpose of the present invention to provide a chest structure as stated, which is of ample strength, very light in weight, and with which a novel hinge structure between the cover and the chest proper may be used, the hinges also being of paper stock and connected in a simple, novel and practical manner, without rivets or the use of any metal. The adjacent sides of the cover and the chest have two thicknesses of the paper material folded or bent at such edges and in the folded edges slots are provided, which in the adjacent sides of the cover and chest, are in conjunction with each other. The hinges at their intermediate portions pass through the slots and have leaf portions which are held between the two thicknesses of the hinged sides of the cover and chest. The hinges are connected without the use of tools very quickly and easily.

An understanding of the invention may be had from the following description, taken in connection with the accompanying drawings, in which:

Fig. 1 is a plan view of a blank from which the lower part of the chest may be made;

Fig. 2 is a perspective view illustrating the steps of folding the blank into receptacle form;

Fig. 3 is a plan of a blank which may be utilized in providing the cover;

Fig. 4 is a perspective view illustrating the folding of the cover to finished condition;

Fig. 5 is an enlarged plan of the hinge used; and

Fig. 6 is a perspective view of the completed chest with the cover in open position.

Like reference characters refer to like parts in the different figures of the drawings.

The lower part of the chest or the receptacle part thereof in which articles are placed may be made from a single sheet of corrugated paper board. By means of suitable dies the blank is cut in the form shown in Fig. 1 and scored for bending on the dash lines shown. A rectangular section 1 provides the bottom of the chest. At each longitudinal side edge two sections 2 and 3 extend outwardly having the same length as the

2

bottom 1 and each of approximately the same width, which width will govern the height of the chest. The sections 2 and 3 are divided by the scored or bending lines between them as shown, and in one of said lines two spaced slots 4 are cut through the material.

At each end of the bottom section 1, end sections 5 and 6 extend in succession outwardly, divided from each other by scored or bending lines and the width of said sections is generally the same as that of the sections 2 and 3. In the immediate end sections 5, a short distance away from the scored lines shown, elongated slots 7 are cut. At each end of each of the inner end sections 5 and separated from the ends of the side sections 2 and 3 by cuts or slots 8, flaps 9 extend outwardly of the form shown, which at their free ends are reduced in width and provided with rectangular recesses 10, between the bodies of the flaps 9 and tabs or ears 11 which are at the outer ends of said recesses.

The chest receptacle is folded on the scored lines, first on the lines between the ends of the bottom 1 and the end sections 5, which sections 5 are turned upwardly and the flaps 9 turned inwardly toward each other and the ends of the flaps at the sides of the chest receptacle are interlocked by engaging the recesses and tabs 11 with each other, as shown in Fig. 2. Thereafter the side sections 2 are turned upwardly and the outer side and end sections 3 and 6 turned downwardly at the inner sides of the box, the locking flaps 9 being covered, and a chest receptacle is made as shown in Fig. 6, having smooth inner sides.

The cover is also made from a single sheet of the same paper material cut by dies to the form shown in Fig. 3. The cover top is provided by a rectangular section 12. At each end are two successive end sections 13 and 14 integrally connected as shown, with suitable bending lines scored or otherwise provided. And from each end of each of the inner end sections 13, flaps 15 extend outwardly in opposite directions. At each side edge of the top 12, side sections 16 extend outwardly and therefrom other sections 17 and 17a, the latter differing from the sections 17 by having a shallow elongated recess 18 cut lengthwise in its edge. The ends of the several sections 16 and 17 and 17a are separated from the flaps 15 by slots 19. Integral with and extending outwardly from the sections 17 is a bottom section 20 of rectangular form, which at its free longitudinal edge has a narrow elongated tongue 21 of substantially the same shape and dimensions

as the elongated recess 18. The scored or bending line between the sections 16 and 17a have two spaced slots 22 cut through the material and spaced from each other the same distances that the slots 4 are spaced.

As best shown in Fig. 4, the end sections 13 are turned upwardly and the flaps 15 inwardly toward each other, the outer end sections 14 then turned downwardly, the section 16 and connected section 17a first turned in an upward direction and then the terminal section 17a turned downwardly as shown, and after the hinges have been located in place, the opposite side section 16 is turned upwardly at the outer sides of the adjacent flaps 15, the connected section 17 turned downwardly at the inner sides thereof, with the terminal section 20 disposed horizontally against the bottom 12. The elongated narrow projection 21 enters the recess at 18 providing a lock against separation.

The hinges (Fig. 5), two of which are used, are made from a single flat piece of the same or similar material. Each consists of two wings or leaves 23 paralleling each other and integrally connected with a bending line midway between their opposite longitudinal edges and each at each end has an outwardly projecting integral ear 24, the ears being separated by slots 25 as shown. The ears 24 may be bent upon the transverse bend scored or bending lines shown, so that either side of the hinge may be inserted through a slot 4 or 22 to connect with the associated sides of the chest receptacle and its cover. Preferably the double thickness side of the cover with which the hinges are connected (Fig. 4) will have staples passed therethrough and through the ends of the hinges located between the side sections 16 and 17a. The use of the staples prevents any possibility of a separation of the two sections 16 and 17a which provide the hinge connected side of the cover. The opposite parts of the hinges pass through the slots 4 and are located between the associated side sections 2 and 3 of the chest receptacle, as shown in Fig. 6. The hinges are bendable on a line between the ends of slots 25 so that the cover may be moved to open or closed position.

The slots 7 in the outer end sections 5 may have bail-like handles 26 associated therewith as shown.

The chest structure described is very practical and useful, its weight is light and its strength is ample. The hinges are of a most economical form and are easily attached. In general, as indicated in Fig. 4, the hinges will first be connected with the cover and later to the lower box or receptacle portion of the chest, though this is not a feature of the invention and the hinges could be first connected to the box instead of the cover. In the practical embodying and building of the chests of the structure described, a very satisfactory product is produced.

The invention is defined in the appended claims and is to be considered comprehensive of all forms of structure coming within their scope.

I claim:

1. A receptacle having a vertical side of two thicknesses of material integrally connected at their upper edges in a smooth, continuous extension from one of said thicknesses of material to the other at said edge, said side at its upper edge having spaced slots through the material at said edge, a cover member having a side of two thicknesses of material integrally connected at the lower edge of a side of the cover, with like spaced slots therein, and flat hinges of flexible material each of substantially rectangular form slotted inwardly for a distance at each end, substantially midway between the side edges thereof to provide two leaves connected by a portion of reduced length, one of said hinges being connected at each of associated slots, one in the receptacle and the other in the cover, with one of the leaves of a hinge between the two thicknesses of material of said side of the receptacle and the other between the two thicknesses of material of said side of the cover, with the shorter length connecting portion between the leaves between said slots in the side of the receptacle and cover.
2. A structure as defined in claim 1, each of said hinges in each leaf thereof being bendable in lines transverse of the leaves of the hinge located at the inner end of each end slot thereof, for the purposes described.
3. In a structure as described, a receptacle having bottom and vertical ends and sides of paper stock material, with a side thereof including two thicknesses of material one outer and the other inner integrally connected at the upper edge of said side, said upper edge of the side having elongated slot openings therethrough spaced from each other, a cover of paper stock material having a top and depending sides and ends at right angles thereto, with a side of two thicknesses of material, one outer and the other inner integrally connected at the lower edge of said side, provided with like slot openings spaced from each other a distance equal to the spacing of the openings in said side of the receptacle, and flexible flat hinges, each of two leaves one secured between the two thicknesses of said side of the cover at each slot opening thereof and the other between the two thicknesses of said side of the receptacle at the slot openings thereof in conjunction with the slot openings in the lower edge of the side of the cover, said leaves of the hinges being integrally connected by a connecting portion between the associated slots in the receptacle and cover sides.
4. A structure as defined in claim 3, each of the leaves of said hinges having a slot extending inwardly from each end substantially midway between the side edges thereof, the inner ends of said slots being spaced a distance from each other slightly less than the length of the slot openings in the said edges of said sides of the receptacle and cover.
5. A structure as defined in claim 4, each of said hinges being transversely bendable about lines across the hinges at the inner ends of the slots therein, for the purposes described.

WILBUR G. ANDERSON, JR.
